DESIGN FOR A GLOW LAMP

Thomas Lamb, New York, N. Y., assignor, by
mesne assignments, to Birdseye Electric Cor-
poration, Dover, Del., a corporation of Dela-
ware

Application October 12, 1935, Serial No. 58,956

Term of patent 14 years

To all whom it may concern:

Be it known that I, Thomas Lamb, a citizen
of the United States, residing in New York, in
the county of New York and State of New York,
have invented a new, original, and ornamental
Design for a Glow Lamp, of which the following is
a specification, reference being had to the ac-
companying drawing, forming a part thereof,
in which.

The figure is a view in elevation of a glow lamp
showing my new design, the metal base being
shown conventionally in dot and dash lines.

Both sides of the lamp are the same in general
appearance.

The dominant feature of my design resides in
the fluted section on substantially the lower half
of the cylindrical body portion.

I claim:

The ornamental design for a glow lamp sub-
stantially as shown and described.

THOMAS LAMB.
